GRATE BAR

Filed Aug. 17, 1929

Inventor:
Theodor Adolph Jessen
by *Kenneth A. Atty.*

UNITED STATES PATENT OFFICE

THEODOR ADOLPH JESSEN, OF HUSUM, GERMANY

GRATE BAR

Application filed August 17, 1929, Serial No. 386,703, and in Austria October 27, 1928.

My invention relates to grate bars and it is an object of my invention to so design a grate bar that the circulation of the air through the fuel bed is improved.

5 To this end I provide on the grate bar a plurality of vanes which are directed against the draught, and make the first rib shorter than the other ribs.

In the drawings affixed to this specification and forming part thereof, a grate embodying my invention is illustrated diagrammatically by way of example.

In the drawings

Fig. 1 is a cross section of two adjacent 15 grate bars,

Fig. 2 is an elevation of one of the bars, and

Fig. 3 is a plan view of the two bars.

Referring now to the drawings, the grate 20 bar *d* is provided with a tapered downwardly extending rib *a* which is equipped with lateral vanes *b* extending from the upper and widest part of the bar to the lower edge of the rib *a*. As will appear from Fig. 2, 25 the vanes *b* are so arranged that their lower ends are leading in the direction of the draught which is supposed to come from the right in Fig. 2. They are preferably curved and reduced or pointed at their lower 30 ends. *c* is the first rib which is shorter than the other ribs, and it will be understood that by thus reducing the length of the first rib the draught is divided and deflected towards the front as well as the rear portion of the 35 bar, and distributed uniformly throughout the length of the fuel bed.

As the ribs are reduced in thickness toward their lower ends the width of the passages between the ribs is conversely reduced 40 toward their upper ends so that the velocity of the flow increases toward the upper ends of the air passages, and the upper parts of the grate bars will be cooled most intensely.

As the air is admitted to the fuel bed not 45 in a vertical but in an inclined direction, it is distributed uniformly and supplies an increased quantity of oxygen to the fuel bed without interfering with the space required for the movement of grate hooks or other 50 implements.

I wish it to be understood that I do not desire to be limited to the exact details of construction shown and described for obvious modifications will occur to a person skilled in the art.

55 In the claim affixed to this specification no selection of any particular modification of the invention is intended to the exclusion of other modifications thereof and the right to subsequently make claim to any modification not covered by the claim is expressly reserved.

I claim:

A grate bar having a body at its upper end which constitutes a bearing surface and 65 is of uniform section throughout its effective length, a tapered rib projecting downwardly from said body, and inclined vanes on said rib, one end vane being shorter than the others and the outer edges of said vanes 70 being within the projected horizontal area of said body.

In testimony whereof I affix my signature.

THEODOR ADOLPH JESSEN.
